UNITED STATES PATENT OFFICE.

CHARLES A. BAILEY, OF CROMWELL, CONNECTICUT, ASSIGNOR, BY MESNE ASSIGNMENTS, TO A. E. CUDWORTH AND F. W. CRANDALL, RECEIVERS FOR HARDWARE & WOODENWARE MFG. CO., OF NEW YORK, N. Y.

DESIGN FOR A GRATING-DOOR FOR TOY BANKS.

41,326.

Specification for Design.

Patented Apr. 25, 1911.

Application filed March 23, 1910. Serial No. 551,217. Term of patent 14 years.

To all whom it may concern:

Be it known that I, CHARLES A. BAILEY, a citizen of the United States, residing at Cromwell, in the county of Middlesex and State of Connecticut, have invented a new, original, and ornamental Design for a Grating-Door for Toy Banks, of which the following is a specification, reference being had to the accompanying drawing, forming part thereof.

The figure is a front elevation of a grating door for toy banks, showing my new design.

I claim:

The ornamental design for a grating door for toy banks, as shown.

CHARLES A. BAILEY.
